UNITED STATES PATENT OFFICE.

GEORGE H. NISBETT, OF HUYTON, ENGLAND.

ELECTRIC CABLE.

SPECIFICATION forming part of Letters Patent No. 655,265, dated August 7, 1900.

Application filed December 28, 1897. Serial No. 663,941. (No model.)

To all whom it may concern:

Be it known that I, GEORGE H. NISBETT, engineer, a subject of the Queen of Great Britain, residing at Huyton, in the county of 5 Lancaster, England, have invented certain new and useful Improvements in Electric Cables, of which the following is a specification.

My invention has reference to the manufacture of electric cables, and more especially to those known as "air-space" or "dry-core" cables adapted for use under water or other external pressures, and more particularly for telegraph and telephone purposes.

15 In order that telegraph and telephone cables may have as low an electrostatic capacity as possible, it is the practice in insulating the copper conductor to so arrange the insulating material as to touch the conductor only on a 20 part of its circumference or at intervals, and in this way the conductor is more or less insulated and surrounded by air. The electrostatic capacity of air being lower and the insulation resistance higher than that of solid 25 insulators, a conductor is in this way obtained having both a low electrostatic capacity and a high insulation resistance. Such cables are commonly made with paper for subterranean work and then served or covered with a sheath 30 of lead to exclude moisture. They can, however, be insulated with any other suitable materials provided the air-space be left. Now the presence of the air-space before mentioned more or less surrounding the conductor makes the cable very liable to collapse 35 under pressure—as, for instance, that to which submarine cables are subjected—this being especially likely when soft metals, gutta-percha, or such substances are used either 40 for the insulating material or the waterproof sheathing; and the object and effect of my invention are to prevent such collapses, and this I do by the construction of cable herein described. The obvious effect of such a collapse of cable if it did not result in the destruction of the cable would at least be to impair its efficiency by closing the air-space.

45 In a cable of any of the dry-core or air-space types according to my invention there is provided over the conductor a cover consisting of a spiral strip or strips of metal or other

strong substances of any suitable shape in cross-section and so arranged and applied as not to press upon the insulated conductor within and to be mechanically strong enough 55 to withstand a crushing strain from without. Over this spiral coil a solid sheath of waterproofing material, such as gutta-percha or other suitable substance, is applied, and this sheath is supported by the spiral cover before 60 referred to, and therefore cannot collapse.

The invention is illustrated in the accompanying drawings, in which—

Figure 1 is an elevation, partly in section, of one form of the cable. Fig. 2 is a transverse 65 section thereof. Fig. 3 is a view similar to Fig. 1 of a modification, and Fig. 4 is a cross-section thereof.

In the form shown in Figs. 1 and 2 the material next the conductor *a* serves both as a 70 support to the conductor in the air-space in which it (the conductor) lies and as a covering by which the air-space is rendered proof against collapse or impairment by pressure from outside—that is to say, it constitutes the 75 part of the cable by which the air-space is made, which supports the conductor in said air-space, insulates it, and provides the means by which the external pressure tending to collapse the air-space is resisted. The 80 part *a'* in this case by which these ends are attained consists of spiral convolutions of a suitable non-conducting material of triangular or equivalent form, the outer edges of which touch or nearly touch each other, 85 as shown, while the spaces, or some of them, of the convolutions stand apart and come next to the conductor and serve to carry it. This spiral covering *b* may consist of ebonite or any other convenient and suitable analogous material. Outside this covering the cover *c*, of gutta-percha or other suitable material by which the air-space is rendered waterproof, is provided, and again outside this are the longitudinal strengthening-wires 90 *d* and coverings of jute or the like. The conductor *a*, as will be seen, will only touch its insulating supporting-spirals *b* at a number of points in the direction of its length, their frequency depending upon the size and shape 95 of the triangular spirals *b* and upon the pitch at which the spirals are wound.

A modification under my invention is shown in Figs. 3 and 4. In this case the insulation-support of the conductor within the cable and the provision of the means of resistance 5 against collapse or impairment due to outside pressure is afforded partly by triangular spiral supports a' , of insulating material, and partly by a flat metal spiral ribbon-cover b , the convolutions of which are a certain distance apart and provide flexibility in the cable. The metal spirals and the internal triangular spirals a' are so disposed in relation to each other that the opening between the convolutions of the cover b stand over the 10 outside or backs of the spirals a' , and so these openings are closed. Outside these parts the waterproofing-coating c is applied, and again outside this waterproof coating the strengthening outside wires and coverings, as in the 15 cables above described, are provided.

In cables of the air-space type where more than one conductor is employed the whole of the conductors may be insulated and stranded together and placed or inclosed within the 20 covering, giving it its power to prevent collapse and forming the air-space, or the conductors may be separate and kept apart within the air-space of the cable with the protective covering surrounding them.

25 In the manufacture of the cable in some cases the spiral protecting cover is wound on over the core of the cable, while in the other case it may be preferable that the protective

covering be made first and the conductor or conductors threaded through it.

35 In the application of the invention thus far described its use in connection only with cables built on the air-space principle has been set forth; but it is to be stated it may be usefully applied in cables other than these—*i. e.*, 40 in cables in which by reason either of the arrangement or of the nature of the insulating materials employed such strengthening or construction to resist external pressures is either desirable or necessary.

45 What is claimed in respect of the herein-described invention is—

1. In an electric cable, the combination with the outer strengthening and insulating layers and the inner conductor, of an interposed separating-coil of substantially-triangular cross-section, substantially as described.

50 2. In an electric cable the combination with the outer strengthening and insulating layers and the inner conductor, of an interposed separator comprising a helically-coiled insulating-support of triangular cross-section having its flat side out and its apex touching the conductor, substantially as described.

55 In testimony whereof I have hereunto set my hand in presence of two subscribing witnesses.

G. H. NISBETT.
